UNITED STATES PATENT OFFICE.

RALPH L. STORM, OF WATERLOO, IOWA.

SIGNALING APPARATUS.

Application filed November 24, 1923. Serial No. 676,697.

To all whom it may concern:

Be it known that I, RALPH L. STORM, a citizen of the United States of America, and resident of Waterloo, Blackhawk County, ⁵ Iowa, have invented certain new and useful Improvements in Signaling Apparatus, of which the following is a specification.

My invention relates to improvements in signaling apparatus, and the objects of my ¹⁰ improvements are the following: to supply a signaling apparatus for location at the crossing of a highway by a railway for mechanical actuation only by a train approaching the crossing along the railway and which ¹⁵ will be of simple and effective construction; to include in said mechanism means operable by the train to set the signal appropriately to give visible warning to persons or vehicles on the highway approaching the crossing ²⁰ from either side; to also include in said mechanism means operated by the train in its further progress to return the signal to a non-signaling position; to include in said mechanism yieldable resilient locking means ²⁵ for the signal to hold it releasably in either a signaling or a non-signaling position; to add to said apparatus lighting means operated by said mechanism to illuminate said signal only when the latter is in its signaling ³⁰ position, and to so mount and construct the initial mechanism operating means as to be unaffected by trains passing thereover in an opposite direction.

With the foregoing and other objects in ³⁵ view which will appear as the description proceeds, the invention resides in the combination and arrangement of parts and in the details of construction hereinafter described and claimed, it being understood that ⁴⁰ changes in the precise embodiment of invention herein disclosed can be made within the scope of what is claimed without departing from the spirit of the invention.

In the drawings:

⁴⁵ Fig. 1 is a diagrammatic front elevation, as seen from one side of a railway, of the mechanism of my signaling apparatus, parts of the same being sectioned or broken away. Fig. 2 is an end elevation of parts of the ⁵⁰ apparatus, with parts removed, broken away or sectioned transversely. Fig. 3 is a detail end elevation of the sliding joint between the signal-plate shaft-crank and the re-setting rod therefor. Fig. 4 is a detail ⁵⁵ view, with parts broken away, and partially in horizontal section of the respective con-

necting means between the setting and re-setting rods and other parts of the mechanism, and Fig. 5 is a detail view showing in plan with parts broken away the setting ⁶⁰ device and its connections. Fig. 6 is a top plan, on a reduced scale, of the railway track at the crossing with the respective setting and re-setting devices of said apparatus.

My device is to be positioned at one side ⁶⁵ of a highway at a railway crossing adjacent to and outside of one of the track rails 40 which are fastened in the usual way upon the cross-ties 39. In place of one cross-tie a wider beam or block 38 is substituted one ⁷⁰ end of which serves as a base for a standard 1 rigidly mounted vertically thereon. Referring now to Figs. 1 and 2, the numeral 4 denotes a spaced pair of apertured bearing bodies seating a horizontal rock-shaft 3 having between said bodies the like detents 21 and 22 extending along the shaft longitudinally midway of said bodies and set at an angle of ninety degrees apart with reversely beveled terminals.

The shaft 3 projects to the left parallel with the adjacent track rails 40 for a distance and a double-faced sign 2 is fixed upon it medially, the shaft traversing the sign and having its outer end supported in an ⁸⁵ apertured bearing 11 on the downturned terminal part of a fixed shaft or rod 6 the right-hand end of which is secured in an apertured block 9 fastened on the upper part of the front face of the standard 1. A brace 5 is ⁹⁰ fixedly and terminally connected between the outer part of the rod 6 and the top of the standard at 8.

Above the sign 2 and clearing it is a ⁹⁵ curvate canopy 75 to largely prevent rain or snow falling upon the sign and is fastened to and supported fixedly on the said rod 6 by bolts 7. Incandescent electric lamps 12 may be mounted upon the under face of said canopy at opposite sides of and to illuminate both faces of the sign 2 when the latter is set at its signaling position to thus be visible to persons at opposite sides of the crossing. These lamps may be supplied with electric current by a small storage battery 14 mounted upon the standard and having its circuit conductors 13 and 17 connected by means of a make-and-break device to be hereinafter described.

The numeral 18 denotes a flat bar spring ¹¹⁰ fastened at its upper end upon the front of said standard and shaped with a medial bend

20 with anticinal faces, the bar having a depending vertical part or terminal 19. The bend 20 is over the shaft 3, spaced therefrom as shown in said Fig. 2 to permit the two 5 elongated detents 21 and 22 to rock past it while in contact therewith during the operation of the signal in setting and re-setting the latter. A coiled tension spring 32 is connected between a screw-eye 31 fixed to the 10 shaft 3 and a pin 33 fixed to the standard 1 below. When the sign 2 is set vertically the spring is but little if at all tensioned, but when the shaft is rocked upwardly ninety degrees to place the sign in a horizontal position, the spring is under considerable tension and ready to react upon the shaft when the latter is released, by its leverage of a crank order upon the projecting screw-eye 31.

Upon the right-hand outer end of the shaft 20 3 is fixed a short crank-arm 34 whose terminal eye or opening is traversed by a bolt or pindle 35 which also slidably traverses the opening of an elongated loop 36 on the upper end of a re-setting rod 37.

25 Below the bar-spring 18 are horizontally alined bearing eyes fixed on said standard to receive and seat the alined inturned extremities 28 of rock-arms 24 and 26 of like shape and having upper inturned and unalined 30 extremities 25 and 23 respectively which thus may clear each other without interference while being rocked to and fro, and these parts 25 and 23 underlie the spring part 19 near the bend 20 in normal contact 35 therewith when the signal is in either of its positions. Eyes on the upper ends of like setting-rods 30 are loosely mounted on the terminal parts or cranks 29 of the arms 24 and 26. A pair of eyes or bearings 42 are 40 fixed on the base-block 38 to receive rock-shafts 76 which have cranked ends 41 and 43, the former being pivotally connected to the lower ends of the rods 30, while the latter are pivotally connected to the horizontal 45 traction-rods 44, the latter being positioned near the outer face of the rail 40. The numeral 48 denotes a rock-shaft which is positioned to rock in bearing-openings in brackets 46 fastened to a cross-tie 39 and has 50 the cranked ends 47 and 49, the former pivotally connected by a pindle-bolt to the abutting end of the traction-rod 44, and a coiled tension-spring 45 is connected between this 55 pindle-bolt and the same cross-tie. This spring tends to rock the crank 47 to the left, to keep the setting-rod 30 lifted and the crank 24-25 swung back to allow the bar-spring 18-19 to normally be untensioned or only so much tensioned as to hold the bend 60 20 engaged with the detent 21.

The numeral 51 denotes a signal-setting bar which lies longitudinally abutting the inner side of the said rail 40 but a little below the level of the latter, and has the upper face of its right-hand end beveled

downwardly at 52 to permit a wheel flange to ride easily upon it without undue shock. The bar has spaced vertical slots 54 traversed by bolts 55, the latter (see Fig. 5) also traversing a hole 54 in the web of the rail 70 and fastened by nuts, the outer ends of the bolts carrying washers 56 and nuts 57, while coiled compression-springs 53 are engaged between these washers and the bar. These springs tend to retain the bar near the rail 75 yieldingly, but the left-hand inner face of the bar is beveled outwardly at 62 to permit the flange of a wheel which approaches from the left to pass between the bar and the rail without depressing the bar, but 80 crowding it away from the rail to pass it. The bar 51 is supported on a pair of coiled compression-springs 60 seated about short studs 61 fixed in the rail base. The crank 49 is bent toward the rail and carries an anti-friction roller 50 engaging the middle under face of the bar 51.

The lower end of the re-setting rod 37 is pivotally connected to a cranked end 73 of a rock-shaft 77 mounted to rock in bearing eyes 72 fixed on said base-block 38. The other cranked end 71 of this rock-shaft is bent toward the rail to carry an anti-friction roller 70 which contacts with the middle of the under face of the re-setting bar 63, the top of the latter being beveled at opposite ends at 64 to allow a wheel-flange to mount it easily going in either direction. The bar 63 is yieldingly elastically supported on a pair of coiled compression-springs 69 as in the case of the setting-bar 51, and has a like connection to the rail, except that the bolts 66 which traverse the slots 65 and openings in the rail are shorter, do not have springs mounted thereon but have washers 105 67 and securing nuts to retain the bar in operative position alongside the rail.

Referring to Fig. 2, the lower detent 22 on the rock-shaft 3 has a contact 15 opposite a fixed contact terminal 16 on the standard 1, said terminals being connected to the lamp conductors and supplying a make-and-break device, so that when the sign 2 is vertically displayed, the detent 22 being directed downwardly, the contact is closed and the lamps are lighted, whereby at night the sign is illuminated by the lamps' reflectors on both sides and visible to the occupant of an approaching vehicle for a long distance, the sign bearing a warning in large letters.

The diagrammatic view of Fig. 6 shows the preferred plan of installation, wherein like setting-bars 51 are provided at opposite sides of the highway but are located several hundred feet away therefrom. But one 125 re-setting bar 63 is necessary, as this bar is actuated by a wheel passing in either direction. The elements of the mechanism are relatively light and therefore may be set or re-set by the flanged wheels of a hand- or 130

motor-car. When a train, or such a car, approaches the crossing, it depresses the setting-bar 51 due to the riding of a wheel-flange over it, and thus the rock-shaft 48 is 5 rocked to draw the traction-rod 44 to the right while tensioning the spring 45, causing the rocking of the rock-shaft 76 and a downward movement of the setting-rod 30, the crank arm 24-25 being swung outwardly to lift the spring bend 20 out of engagement with the detent 22, so that the 10 spring 32 may react to rock downwardly the rock-shaft 3 to position the sign 2 vertically as shown in Fig. 1, its signaling position. 15 As shown in Fig. 3, this rocking of the shaft 3 swings upwardly the crank 34 so that the pintle 35 passes to the top of the loop 36 of the re-setting rod 37. This loose or sliding joint is provided to prevent any 20 undue strains or breakages in said connected parts while in operation. Then also, when the re-setting of the signal is to be accomplished, the pintle is positioned at the top of the loop ready to receive the down draft 25 from said rod.

As the train passes off the setting-bar 51, the bar-spring returns to engage the detent 21 in its bend, until the wheels of the train are near the highway when they ride upon 30 the re-setting bar 63, depressing it. This rocks the crank 71 downwardly so that the re-setting rod 37 is moved downwardly rocking the shaft 3 back again to its initial position where the signal sign 2 is swung over 35 to a horizontal non-signaling position. The lower detent 22 becomes engaged with the bend 20 of the bar-spring 18 and the contact of the terminals 15 and 16 is opened to extinguish the lamps 12.

40 Having described my invention, what I claim as new, and desire to secure by Letters Patent, is:

1. In a signaling apparatus, in combination, a signaling device, operable means for shifting said device to a signaling position, other means operable for shifting said device to a non-signaling position, and resiliently controlled different interlocking elements operable alternately upon said means 45 to respectively releasably hold said signaling device in either its signaling or its non-signaling position.

2. In a signaling apparatus, in combination, a signaling device, alined resiliently 50 controlled pressure elements independently connected to said device for alternated actuations thereof to initially actuate the device for signaling and then after an interval to render the device inactive, and means controlled by one series of said pressure elements to releasably interlock with said signaling device to retain it in either its active or its inactive position.

3. In a signaling apparatus, in combination, a signaling device supported for move-

ments in different directions, resiliently-controlled means for releasably securing the device at certain limits of its movements, and independent mechanisms operable upon said signaling device for alternated actuations 70 thereof, each mechanism including resiliently-controlled tread-elements arranged in alinement for successive actuation by the pressure of a wheel riding thereover to alternate the actions of the mechanisms upon the 75 signaling device while the wheel is moving in one direction only.

4. In a signaling apparatus, in combination, a signaling device mounted movably to be positioned in either a signaling or a 80 non-signaling position, yielding resilient trip-devices positioned alongside a line of railway rails in the path of progressive movement of the flange of a wheel traveling upon the rails to be depressed reactively thereby in succession, one of the trip-devices being mounted and resiliently controlled for sidewise movements to and from the rails and shaped at its following end to be there further spaced from the rails to allow the flange of a wheel moving in an opposite direction to enter the interspace and pass between the trip-device and the rails without actuating the device, and said trip-devices 85 being operatively connected to said signaling-device for successive actuations thereof to place it in a signaling and a non-signaling position alternately.

5. In a signaling apparatus, in combination, supporting-means, a rock-shaft mounted thereon and having a terminal double-face warning sign, means positioned within a line of track-rails for pressure actuation in succession by the flange of a wheel traversing the rails in one direction to rock said shaft alternately to and fro to place the said sign in first a vertical displaying position to be seen at a distance from either side of the track-rails and second in a horizontal non-display position, and devices included in said means for automatically releasably locking the rock-shaft in either of said positions.

6. In a signaling apparatus, in combination, supporting-means, a rock-shaft mounted thereon and having a terminal sign set parallel to the line of adjacent track-rails to be rocked to either a horizontal or a vertical position, releasable locking means for said shaft to hold it in either of said positions, electric illuminating means for said sign in circuit with a source of electric current containing a circuit-closer, said circuit-closer having terminals, one fixed, and the other mounted upon said rock-shaft, whereby when the rock-shaft is rocked to place said sign in its vertical position the circuit is closed by contact of the movable with the fixed terminal.

7. In a signaling apparatus, in combina-

- tion, supporting-means, a canopy bracketed thereon, a rock-shaft mounted upon the supporting-means under said canopy and having a signaling sign also under said canopy, vertically-movable resiliently controlled tread-elements positioned alongside the inner face of a line of track-rails adjacent said supporting-means and in the path of the flange of a car-wheel passing along the 10 rails whereby the flange will successively depress said elements while traveling in one direction, and a wheel-flange will depress one only of said elements while traveling in an opposite direction, and operative connections between said tread-elements and said rock-shaft adapted to rock the shaft alternately to place said sign in either a signaling or in a non-signaling position.
8. In a signaling apparatus placed near 20 the intersection of a highway and a railway track, like but reversed resiliently-controlled

tread-elements positioned at opposite sides of and spaced from said highway alongside the inner face of one line of the railway track-rails, a signaling-device in said apparatus movable from a display to a non-display position, independent operative connections between said signaling-device and said tread-elements, a re-setting tread-element, resiliently-controlled, positioned alongside said track-rails intermediate the first-mentioned tread-elements, and operative connections between the re-setting tread-element and said signaling-device, the said tread-element being operable to move the signaling-device to a non-display position after either of the other tread-elements has been actuated to move the signaling-device to a display-position.

Signed at Waterloo, Iowa, this 21st day 40 of November, 1923.

RALPH L. STORM.
